WARNING AND SIGNALING LIGHT HAVING
OSCILLATABLE LAMP UNITSArthur C. Heehler and Thomas E. McDowell, Chi-
cago, Ill., assignors to The Pyle-National Com-
pany, Chicago, Ill., a corporation of New Jersey

Application January 13, 1950, Serial No. 138,442

11 Claims. (Cl. 177—327)

1

This invention relates generally to illumination apparatus for warning and signalling purposes and more particularly relates to a warning and signalling light having one or more oscillatable lamp units adapted to produce a changing pattern of light.

According to the general features of the present invention, a casing may be provided having a mounting plate adjustably supported therein. A pair of self-aligning bearings or other type of swivable support such as flexible diaphragms are carried by the mounting plate in predetermined spaced relationship and a pair of lever arms extend through each of the bearings or supports for oscillatory movement therein.

A sealed-beam type lamp unit is rigidly connected to the free end of each of the lever arms and the other end of each of the lever arms is connected by a connecting rod or link. The link is provided with a self-aligning bearing effecting a driven connection with an eccentric rotary drive powered through a gear box connected to an electric motor. Thus, upon energization of the motor, both of the sealed-beam type lamp units are oscillated in a conical path to project an oscillating beam of light in changing pattern for warning or signalling purposes.

A lens assembly may be fitted on the front end of the lamp structure so that a lens will lie in registry in front of each of the sealed-beam type lamp units, one of the lenses being of clear glass and the other being of any desired hue.

The energization of the lamp structure may be so controlled as to selectively produce various colored beams of warning light.

It is an object of this invention, therefore, to provide a novel linkage for an oscillatable warning light which is pivotally supported for oscillatory movement in self-aligning bearing means and which may be suitably oscillated so that lamp units carried thereby are moved to produce a changing pattern of light.

Another object of the present invention is to provide a universal type self-aligning swivel support or bearing for a lever arm carrying a lamp unit on the end thereof so that the lever arm may be oscillated by a driving means to move the lamp unit as in producing a changing pattern of light.

Another object of the present invention is to provide a warning and signaling light having a plurality of lamp means movably supported in predetermined spaced relationship and so constructed and arranged as to direct a merging beam of light, the lamp means being associated

2

with driving means so as to permit synchronous oscillation of the lamp means.

A further object of the present invention is to provide a multi-lamp unit warning light mounted for oscillatory movement on an adjustably suspended support plate.

It is a further object of the present invention to provide a warning and signalling light of simplified construction incorporating therein a reduced number of elements which are easy to manufacture, durable in use, and efficient in operation.

Many other advantages, features and additional objects of the present invention will become manifest to those versed in the art upon making reference to the detailed description which follows and the accompanying sheets of drawings in which:

Figure 1 is a cross-sectional side view of a lamp unit according to the present invention with parts shown in elevation and with parts broken away and with parts removed for the sake of clarity;

Figure 2 is a cross-sectional view looking into the back end of the structure and showing additional details and construction of the lamp unit of Figure 1;

Figure 3 is a front elevational view in reduced scale of the lamp unit of Figure 1;

Figure 4 is a somewhat schematic wiring diagram showing a control system for the warning and signalling light of the present invention; and

Figure 5 is a fragmentary view of a simplified universal support joint as may be employed according to the present invention.

As shown on the drawings:

The warning and signalling light of the present invention is indicated generally by the reference numeral 10 and includes an open-ended casing 11 closed by a door 12 hingedly connected to the casing 11 as at 13. A gasket 14 may be carried by the door 12 for seating against the edges of the casing 11 when the door 12 is in the closed position and locked to the casing 11 by latch means indicated generally by the reference numeral 16.

On the inside of the casing 11 are provided a plurality of spaced bosses 11a, preferably three in number, each of which may be provided with a threaded aperture 17 to receive an adjusting bolt 18 therein.

A support element in the form of a plate 19 is carried by the adjusting bolts 18 and is normally spring-biased away from the bosses 11a by a

plurality of resilient members 20, one surrounding each of the adjusting bolts 18. Thus, the alignment of the support element or plate 19 may be selectively varied by turning the respective adjustment bolts 18 within the threaded apertures 17 against the bias of the resilient elements 20. The limits of adjustment may be determined by spacer sleeves 21 which are adapted to surround each resilient element 20 and adjusting bolt 18 and to seat upon the shoulder presented by the boss portions 11a.

As may be clearly seen in Figure 1, a plurality of universal type self-aligning swivel bearings indicated generally by the reference numeral 22 are provided in predetermined spaced relationship on the support element or plate 19 so as to lie in registry with one of a plurality of apertures 23 defined by the support element or plate 19.

Each of the bearings 22 includes a housing 24 which may be secured to the plate 19 by fasteners 26. An outer race 27 defining a segmental spherical seat is carried within the housing 24 and seats a plurality of ball bearings indicated generally by the reference numeral 28.

A plurality of lever arms is provided to extend through the bearings 22. As shown in this particular embodiment, an upper lever arm 29 and a lower lever arm 30 are shown, each of which is constructed to carry an inner race 31 which is appropriately grooved to cooperate with the ball bearings 28.

Retainers 25 complete the bearing structure and retain the ball bearings within the raceway.

If desired, a simplified universal type support joint may be provided in place of the self-aligning bearings. For example, as shown in Figure 5, a lever arm 29' is shown supported for oscillatory movement by a flexible diaphragm 22' mounted on the support plate 19 by means of a washer 24' and fasteners 26'.

A lamp unit is rigidly connected on the end of each of the lever arms 29 and 30, such provision including in this embodiment a lamp unit 32 connected to the lever arm 29 and a lamp unit 33 connected to the lever arm 30. The other end of the lever arms 29 and 30 are joined by a connecting rod or link indicated generally by the reference numeral 34.

The lamp units 32 and 33 are of identical construction and include a housing 36 which may be firmly assembled to a boss 37 by means of fasteners 38, the boss 37 being, in turn, firmly connected to the lever arms 29 and 30. Each of the housings 36 carries a retaining flange 39 which is so constructed as to seat the annular shoulder 40a of a sealed beam type lamp 40.

The sealed-beam lamp 40 may be positioned and secured in the housing 36 by means of a holding ring 41 telescopically associated with the retainer flange 39.

In order to accommodate dimensional variations, the holding ring 41 is preferably provided with an inner flange 43 supported by a plurality of resilient elements 42 so as to yieldingly clamp the annular shoulder 40a of the sealed-beam lamp 40 against the retainer flange 39. The holding ring 41 and the retainer flange 39 may be adapted for quick-coupling action by pin and bayonet slot connections indicated generally by the reference numeral 44 (Figure 1).

It will be understood that each of the sealed-beam lamps 40 will be provided with the usual conductor wires 46 which are connected to a flexible braided wire conductor 47 connected to a

terminal block 48 carried on the support element or plate 19. The connection is effected by means of a binding post 49 supported in a bushing 50 made of electrically non-conductive material carried by the housing 36. A shield of electrically non-conductive material indicated by the reference numeral 51 may be provided on the external surface of each of the lamp units 32 and 33 so as to prevent the flexible braided wire conductors 47 from short-circuiting through the housing 36 of each of the lamp units 32 and 33 during operation of the light.

As may be clearly seen in Figure 1, a plurality of universal type self-aligning swivel bearings indicated generally by the reference numeral 22 are provided in predetermined spaced relationship on the support element or plate 19 so as to lie in registry with one of a plurality of apertures 23 defined by the support element or plate 19.

Each of the bearings 22 includes a housing 24 which may be secured to the plate 19 by fasteners 26. An outer race 27 defining a segmental spherical seat is carried within the housing 24 and seats a plurality of ball bearings indicated generally by the reference numeral 28.

A plurality of lever arms is provided to extend through the bearings 22. As shown in this particular embodiment, an upper lever arm 29 and a lower lever arm 30 are shown, each of which is constructed to carry an inner race 31 which is appropriately grooved to cooperate with the ball bearings 28.

Retainers 25 complete the bearing structure and retain the ball bearings within the raceway.

If desired, a simplified universal type support joint may be provided in place of the self-aligning bearings. For example, as shown in Figure 5, a lever arm 29' is shown supported for oscillatory movement by a flexible diaphragm 22' mounted on the support plate 19 by means of a washer 24' and fasteners 26'.

A lamp unit is rigidly connected on the end of each of the lever arms 29 and 30, such provision including in this embodiment a lamp unit 32 connected to the lever arm 29 and a lamp unit 33 connected to the lever arm 30. The other end of the lever arms 29 and 30 are joined by a connecting rod or link indicated generally by the reference numeral 34.

The lamp units 32 and 33 are of identical construction and include a housing 36 which may be firmly assembled to a boss 37 by means of fasteners 38, the boss 37 being, in turn, firmly connected to the lever arms 29 and 30. Each of the housings 36 carries a retaining flange 39 which is so constructed as to seat the annular shoulder 40a of a sealed beam type lamp 40.

The sealed-beam lamp 40 may be positioned and secured in the housing 36 by means of a holding ring 41 telescopically associated with the retainer flange 39.

In order to accommodate dimensional variations, the holding ring 41 is preferably provided with an inner flange 43 supported by a plurality of resilient elements 42 so as to yieldingly clamp the annular shoulder 40a of the sealed-beam lamp 40 against the retainer flange 39. The holding ring 41 and the retainer flange 39 may be adapted for quick-coupling action by pin and bayonet slot connections indicated generally by the reference numeral 44 (Figure 1).

It will be understood that each of the sealed-beam lamps 40 will be provided with the usual conductor wires 46 which are connected to a flexible braided wire conductor 47 connected to a

casing 11 via the apertures 67 and 68 of the door 12 may be readily and easily adjusted by means of the suspended support element or plate 19.

In operation, the motor 64, or any equivalent driving means, will rotate the eccentric crank 60 so as to impart an oscillatory motion to the linkage via the connecting rod or link 34. The entire linkage will oscillate as an integral unit so as to pivotally oscillate the lever arms 29 and 30 in the bearings 22, thereby moving the lamp units 32 and 33 in a conical path to produce a changing pattern of light. In the present embodiment, the structure is so arranged as to oscillate between an upper displacement axis and a substantially horizontal axis.

Referring now to Figure 4, the control system for the warning and signaling light of the present invention may be described. As is diagrammatically shown in Figure 4, an upper lamp unit 32 and a lower lamp unit 33 are incorporated in a control circuit. For purposes of explanation, it is assumed that the upper lamp unit directs its beam of light through a lens 71 of red hue, such color oftentimes being desirable if the warning and signalling light of the present invention is employed in a locomotive installation.

For projection of a stationary beam of clear light, by a manual operation, the master switch is moved to manual position and the selector switch is moved to white position, thereby completing the circuit to the lower lamp unit 33 and producing a beam of clear light.

Since the operation of a motor 64 is regulated by a separate motor control switch, the beam of light projected by the lamp 33 will be stationary until the control switch is moved to the "run" position, whereupon the linkage of the light structure 10 will be oscillated to move the lamp unit 33 thereby producing a changing pattern of light.

If it is desired to "inch" the beam of light projected by the lamp unit 33 around to different points along the conical path described by the projected beam of light, as would be desirable if the warning and signalling light 10 was installed upon a railroad locomotive, the motor control switch may be selectively held in the inching position as long as is necessary to complete the circuit to the motor 64 and move the lamp unit 33.

If a beam of red light is desired and the master switch is on "manual," the selector switch is moved to the red position whereupon the coil of a relay 76 will be energized and the switches of the relay 76 will be closed. The circuit to the lamp unit 32 will be completed, energizing the light, and the circuit to the motor 64 will also be completed so that a gyrating beam of red light will be projected.

It will be noted that a pilot light is connected across the leads to the lamp unit 32 so that the operator will always have a ready indication of the energization thereof. Should the lamp unit 32 fail, the coil of the relay 76 will be deenergized, the relay switch in the pilot light circuit opened, and the pilot light will be extinguished.

In automatic operation, the master switch is moved to the automatic position, thereby cutting in an additional control switch which is regulated by a pressure responsive control device as is frequently employed in connection with the air brake system of a railroad train.

In automatic operation, the selector switch may be moved to the white position so as to produce a stationary beam of white light. However, this particular setting will be overcome by operation of the pressure responsive control device,

for example, if an emergency condition detected by the device should occur; or, if the light 10 is employed on a railroad train, if a change in air pressure should occur, as in the setting of the train brakes, so that the switch controlled by the pressure responsive control device will be moved downwardly, thereby bypassing the selector switch and automatically initiating red operation.

10. Restoration of normal air pressure and subsequent inactivation of the pressure responsive control device will again restore normal white operation unless, as an added safety measure, a control device is employed which requires a 15. manual resetting. With a manual reset, the red operation will continue until the reset is deliberately actuated. This feature may be desirable in the event of an emergency condition, for example, a prolonged halting of a railroad train 20. where normal air pressure is restored before the emergency is ended.

- In automatic operation, a red beam of warning light may be projected by setting the selector switch to the red position. It will be apparent 25. that actuation of the pressure responsive control device will not affect such operation because the switch controlled by the pressure responsive control device merely effects bypassing of the selector switch, which is already in red position. 30. It will be noted that a dimmer resistance is provided on the selector switch. By such provision the lamp may be dimmed selectively by the operator.

- Although it is contemplated that various minor 35. modifications may be made to the structure herein described by way of illustrative example only, it should be understood that we do not wish to be limited to precise mechanical details but wish to embody within the scope of this patent all such 40. modifications as reasonably and properly come within the scope of our contribution to the art.

We claim as our invention:

1. A warning and signalling light comprising an open-ended casing, a support plate therein, at 45. least two lever arms extending through the support plate, said plate having means to support said lever arms for oscillatable movement, light source means on one end of each lever arm on one side of the support plate to direct beams of light through the open end of the casing, driving means on the other side of the support plate, and a driven connection between the driving means and the lever arms to oscillate the other end of the lever arms whereby the light source means on 50. said one end of the lever arms will be concurrently oscillated to produce moving beams of light.

2. A warning and signalling light comprising an open-ended casing, a support plate, adjustable 55. alignment means to movably suspend the support plate in the casing, a plurality of lever arms extending through the support plate, said plate having means to support said lever arms for oscillatory movement, a light source unit on one end of each of said lever arms, means pivotally joining the other end of the lever arms, and motor means having a driving connection with the lever arm joining means to oscillate the other end of each of said lever arms whereby said light 60. source units will be concurrently oscillated to produce moving beams of light.

3. A warning and signalling light comprising an open-ended casing, a support plate, means to suspend the support plate in the casing, a plurality of self-aligning bearing means carried by 65. 70. 75.

the plate, a link extending through each of the bearing means and supported thereby for oscillatory movement, a light source unit on one end of each of the links, means pivotally joining the other ends of the links, motor means, an eccentric crank connected thereto, and a self-aligning bearing means interconnecting the crank and the link joining means whereby the other end of said links may be pivotally oscillated to concurrently move the light source units, thereby producing movable beams of light.

4. A warning and signalling light comprising an open-ended casing, a door closing said opened casing, a plurality of lenses mounted in spaced apart relationship on said door, one of which may be colored, a plurality of light source units corresponding in number to said lenses movably mounted in said casing, each light source unit lying in registry with a corresponding one of said lenses, and means to move said light source units, whereby movable beams of different colored light may be projected outwardly through the lenses.

5. A warning and signalling light comprising an open-ended casing, a plurality of lenses mounted in spaced apart relationship on the open end of the casing, one of which may be colored, a plurality of light source units corresponding in number to said lenses movably mounted in said casing, each light source unit lying in registry with a corresponding one of said light source lenses, means to move said light source units, and means to selectively energize said light source units, whereby a selectively colored beam of light may be projected outwardly of the casing through said lenses.

6. In a warning and signalling light, self-aligning bearing means, a plurality of links, each of said links being pivotally supported in said bearing means intermediate the ends thereof, light source means mounted on one end of each of said links, a connecting arm pivotally joining the other ends of the links, and motor means drivingly connected to said connecting arm to oscillate said connecting arm, all of said links being pivotally displaceable simultaneously in the bearing means by the motor means to concurrently move all the light source means, thereby providing movable beams of light.

7. A control system for a warning light comprising a first light source unit, a second light source unit, motorized means to move both of the light source units to produce a changing pattern of light, selector switch means to selectively

energize the light source units, control switch means to selectively control the energization of the motorized means, switch means having elements responsive to a change of a variable condition and arranged to selectively by-pass the selector switch means in the event a change of a variable condition occurs, and master switch means to selectively by-pass the switch means upon actuation thereof.

10 8. In a warning and signalling light, a plurality of lever arms, means intermediately supporting said lever arms for universal oscillatory movement, link means pivotally connecting one end of each of the arms, light source means on the other end of each of the arms to project beams of light and oscillating means connected to the link means, whereby said lever arms and said light source means will be concurrently oscillated to produce a changing pattern of light.

15 9. A warning and signalling light structure as defined in claim 8 wherein said means intermediately supporting said lever arms comprise a support plate having an apertured flexible diaphragm to oscillatably support each of said lever arms.

20 10. A warning and signalling light structure as defined in claim 8 wherein said means intermediately supporting said lever arms comprise a support plate having a universal type self-aligning swivel bearing to oscillatably support each of said lever arms.

25 11. A warning and signalling light comprising a casing, a plurality of lenses aligned in spaced apart relationship in one wall of said casing, a light source unit for each of said lenses movably mounted in said casing in alignment with the corresponding lens, means to selectively energize said light source units, and means to move said light source units to project movable beams of light outwardly of said casing through said spaced apart lenses.
